UNITED STATES PATENT OFFICE.

GEORGE A. CARDWELL, OF BROOKLYN, NEW YORK, ASSIGNOR OF TWO-THIRDS TO FREDERICK K. FITCH, OF NEW YORK, AND JOSEPH T. MURRAY, OF NEWARK, NEW JERSEY.

HARMONIC PRINTING-TELEGRAPH.

SPECIFICATION forming part of Letters Patent No. 315,122, dated April 7, 1885.

Application filed October 1, 1884. (No model.)

To all whom it may concern:

Be it known that I, GEORGE A. CARDWELL, a citizen of the United States, residing at Brooklyn, in the county of Kings and State 5 of New York, have invented certain new and useful Improvements in Multiple Printing-Telegraphs; and I do hereby declare the following to be a full, clear, and exact description of the invention, such as will enable others skilled in the art to which it appertains to make and use the same, reference being had to the drawings, wherein—

Figure 1 is a diagram of my invention, and Figs. 2 and 3 are perspective views of a pair 15 of grouped actuating-magnets.

My invention relates to an improvement in electric telegraphy; and it consists in a novel application of the multiple system of transmission, and particularly of what is known as 20 the “Gray harmonic system,” whereby the rapidity of transmission and reception is greatly accelerated under conditions that render the printing of the received messages possible at a speed and with a certainty hitherto 25 unattainable.

My invention contemplates, and through the agencies which I employ effectually carries out, what may be appropriately termed a “permutation of the multiple principle”— 30 that is to say, by the combination in groups or couples of given electrical pulsations I am enabled to enlarge upon and increase the application of the separately-transmitted pulsations, and accomplish as many distinct acts as 35 from a given series of fundamental pulsatory current there may be formed groups, combinations, or permutations. These distinct acts may be, and as developed in the system which I am about to describe are, the printing or 40 recording, respectively, of a letter of the alphabet and, if necessary, a number or arbitrary sign.

As my invention can be more thoroughly understood in its application to the harmonic system of multiple telegraphy, I have selected the latter as the basis of my description.

Let it be supposed, for instance, that I have at command, say, six harmonic tones—viz., G A B C D E. Now, according to the Gray

harmonic system, I can send all or any number of these tones simultaneously over the one circuit, and cause each tone to affect its own receiver or relay; but by a system of combinations in the receiver which I employ I can, by the simultaneous transmission of any group 50 of tones and the responsive action of a corresponding group of receiving-relays, effect an act or result which is the direct and invariable sequence of such combination. Thus, should I send together the tones C E, the result will be the actuating of mechanism which will print the character “g,” while if I send C and G the character printed will be “i,” and so on, and if, instead of combinations, I should send single tones, each tone will cause the 65 printing of the character allotted to the selected tone.

In the accompanying drawings I have illustrated and in the following description I shall specify sufficient of an organized system to 70 clearly indicate the character of my invention, and shall therefore limit myself to a specific description of the receiver. Such a receiver is adapted to respond to combination tones, no matter by what devices the 75 same are transmitted, so that a specific description of a transmitter particularly designed and adapted to be used in connection with my system of receiving will be unnecessary, and will be reserved as the subject of a 80 future application.

Again, to render the description concise, I shall assume that the Gray harmonic system is well understood and need not be explained, or its principles dwelt upon further than may 85 be incidentally suggested or warranted by the novel conditions of its use.

Referring to the accompanying drawings, A designates the main-line wire of a harmonic telegraph, leading to ground at a receiving-station through the magnets B C D E F G, which are provided with the appurtenances of a Gray harmonic relay, so that each needed armature will respond to its appropriate tone and to no other, and when so responding will 90 open a local-battery circuit, a b c, &c., which is normally closed upon a secondary and open circuit relay, a' b' c', &c.

I term $a' b'$, &c., "open-circuit" relays, because they are normally in an energized state, and, under conditions hereinafter explained, close another local circuit or circuits when 5 their armatures are retracted by the de-energizing of their coils.

The relation of the magnets B, C, &c., and the magnets $a' b'$, &c., is the same as exists between the harmonic relay and sounder under the usual conditions of harmonic telegraphy.

I have suggested that each individual tone will effect the printing of a single character, and now before going into detail as to the precise means by which the secondary relays are controlled so as to respond to both single and combined tones, I would suggest a reference to the diagram figure, which illustrates the general principle of action and the main path 15 of circuits by which the printing under single tones is accomplished.

1 in the diagram is a local battery, from which a line, 2, leads through back stops, 3, of armatures 4, &c., and thence by lines 5 through 30 all the armatures 4, &c., above which are other stops, 6, &c., each having a line to a printing-magnet, 7, &c., and each being in a branch and normally-open circuit with battery 1. Now, supposing it were desired to print the letter "b" in response to the tone C, the tone 25 is "transmitted," and immediately harmonic relay C responds, opening its local circuit and causing armature 4' to fly back against stop 6'. Circuit from battery 1 is now through all 35 the back stops or continuous line 2, thence through armatures until 4' is reached, when the current passes to printing-magnet 7', and thence to battery, all the other printing-magnets being out of or on open circuit. It 40 is obvious that any other tone may be similarly made to control and effect the printing of its appropriate character. This much understood, I will now explain in detail the means by which two combined tones will cause a 45 dependent character to be printed.

The armatures of the secondary relays are pivotal or provided with pivotal arms G' , Figs. 2, 3, and carry front and back contacts, $h h'$, and lower insulated contacts, *i i*. The 50 points $h l'$ and $h' l$ are respectively connected by lines $m m'$. Stops h are opposed to stationary contacts $l l$, stops h' oppose contacts l' , and stops *i* face contacts l^2 , all being properly insulated.

55 In the drawings, Figs. 2 and 3 are designed to represent under two conditions a pair of armatures belonging to a harmonic group or couple—say G F, which is arranged for printing the character, say, "I." Then the stop l' of each is connected by a line, m , with the stop h of the other, while a line leads from a stop, l , above each armature, as already mentioned in explanation of diagrams, to a magnet, 7. The stops $l^2 l'$ are in circuit with a local battery, M, and a printing-magnet, M', adapted 60 to print the character "I." Now, normally, the

armatures G' being closed or down, the current vibrations or pulsations corresponding to a single tone will cause the retraction of but one of said armatures, as shown in Fig. 3, and 70 the circuit will be from battery 1 and line 2, through line k and by way of the attracted armature and stops $h' l'$ thereof, through the line m , joined to said stop l' , thence to and through stops $h l$ of the retracted armature, to 75 and through printing-magnet 7, back to battery 1, all other circuits being open; but should currents corresponding in vibration to two tones be sent simultaneously, both armatures $G' G'$ will be retracted and circuit completed 80 through *i i l' l^2*, line k' , battery M, and printing-magnet M', as shown in Fig. 2, all other circuits of this group being open.

By an analogous arrangement of circuits and connections all the secondary relays may 85 be grouped together in pairs.

The mechanical details of the printer do not properly constitute a part of my system, and as their principles are well understood and susceptible of much variation, I do not deem it 90 necessary or expedient to describe them.

I have shown how separate printing-magnets may be energized, and it is but a question of mechanical skill and expedient to couple these magnets to their appropriate 95 printing devices and appurtenant parts.

The details of the printing devices I reserve, to make them the subjects of future applications.

By the term "tone" herein used I wish to 100 be understood as meaning the vibration or pulsation corresponding to the tone.

While I have specifically described my invention in its application to the harmonic system of multiple telegraphy, I do not wish 105 to be understood as limiting myself thereto, as any system of multiple transmission wherein separate currents over a single circuit wire or conductor energize separate and independent receiving-instruments may be employed.

110 While the foregoing description pertains specifically to a system whereby the particular result accomplished is the selection and energization of printing or recording magnets through the agency of simultaneously-transmitted currents of different characteristics, the printing or recording instrument being understood to be at a main receiving-station, it is obvious that the same means may be employed in selecting special lines or circuits 115 leading from such station to different points, and in using such lines for the transmission of relayed Morse or other telegraphic signs or signals. Thus, assuming that the printing-magnets represent "sounders" located at distant points, then the manipulation of the transmitting-keys according to the "Morse" method will effect the relaying of the circuits of said magnets, so that a particular line will respond to the simultaneous transmission of two different currents in substantially the same manner as a particular printing-magnet responds,

Having described my invention, I claim—

1. In a multiple telegraphic apparatus, the combination of two or more relays responsive to different currents, each controlling a receiving-magnet and its circuit, and conjointly controlling a third receiving-magnet and intermediate electro-magnetic devices, as set forth. 5
2. In a multiple telegraphic printer, the combination of two or more relays responsive to different currents, a printing-magnet, and intermediate electro-magnetic devices, as set forth, whereby a single character will be printed in obedience to the conjoint action of the two relays. 10
3. In a multiple telegraphic printer, the combination, with relays, printing-magnets, and intermediate devices, whereby said magnets will respectively respond to grouped or simultaneously-produced but independent currents, of printing-magnets and appurtenant devices, as set forth, which will respond to single or individual currents, substantially as described. 15
- 25 4. In a multiple telegraph, the combination of two or more relays, with their local-battery circuits, two or more secondary relays in

said local circuits, one or more supplementary circuits, and generators, with a series or system of circuits and contacts, whereby the operation of two intermediate relays will effect an operation of two secondary relay-armatures and close a normally-open circuit upon a magnet, substantially as described. 30

5. In a printing-telegraph in which printing-magnets print in response to the action of single relays, the combination, with said relays and printing-magnets, of second relays, printing-magnets in supplementary circuit or secondary local, coupled secondary relay-armatures, contacts, and branches, whereby certain printing-magnets will respond to single currents, and others will respond to grouped or simultaneously-produced currents, and whereby, when certain currents are grouped, their individually-dependent printing-magnets will remain passive. 35 40 45

In testimony whereof I affix my signature in presence of two witnesses.

GEORGE A. CARDWELL.
